INVENTOR:

WILLIAM H. HEISE

BY,

Fred W. Davis

ATTORNEY.

UNITED STATES PATENT OFFICE.

WILLIAM H. HEISE, OF LOS ANGELES, CALIFORNIA, ASSIGNOR TO BIG ROCK RANCH COMPANY, OF LOS ANGELES, CALIFORNIA, A CORPORATION OF CALIFORNIA.

HEARSE.

Application filed August 26, 1924. Serial No. 734,240.

My invention relates to hearses and more particularly to automobile hearses. There is a very general tendency to minimize as far as possible those features of final interment which have become conventionally associated with funerals. It is now the general desire to do away with the usual trappings found on the standard hearse and to substitute therefor an ordinary sedan or limousine automobile, thus giving the bereaved the illusion that the final ride of the deceased is not necessarily something radically different or more heart rending than other rides enjoyed during the life then terminated.

It is an object of my invention to provide means by which a standard sedan automobile can be readily adapted for use as a hearse without radically changing its outside appearance.

Hearses used at the present time usually provide for the insertion of a casket thereinto thru the rear end thereof. In order not to obstruct street traffic, hearses are always parked parallel to the curbing. This compels the pall bearers, when placing a casket in the hearse, to step down from the curbing into the street. This increases the burden on the pall bearers, who are sometimes rather infirm, and also detracts from the solemn appearance of the funeral service.

It is an object of this invention to provide a means which will permit the insertion of a casket into a hearse from the side thereof, and thereby eliminate the disadvantages of the present type of hearse. To accomplish this object, I provide a novel type of platform which is movable into a position in which it extends outwardly through a side opening in the hearse, so as to allow the placing of a casket thereon, and which may then be moved into a normal position permitting a closing of the side doors of the hearse.

It is also an object of this invention to provide a platform which is freely movable. This is accomplished by the provision of separate means for supporting the platform and separate means for guiding the platform through a predetermined path.

It is a further object of the invention to provide a means for locking the platform in normal position within the hearse.

It is still a further object of the invention to provide a means which assures the maintaining of a casket in proper position upon a platform.

Further objects and advantages of the invention will be made evident hereinafter.

Referring to the drawings which are for illustrative purposes only,

Fig. 1 is a diagrammatic plan view showing the use of my platform in conjunction with a hearse.

Fig. 2 is a sectional view of the platform taken substantially as indicated by the line 2—2 of Fig. 1.

Fig. 3 is a bottom plan view of my platform which clearly depicts the arrangement of guiding rollers and supporting rollers.

Fig. 4 is a section taken substantially as indicated by the line 4—4 of Fig. 3, this view showing one type of supporting roller which may be employed in this invention.

Fig. 5 is a sectional view taken substantially as indicated by the line 5—5 of Fig. 1, this view clearly illustrating the type of locking arrangement employed for retaining the platform in normal position.

In the drawings, my invention is shown as being employed in a hearse 11, which, in lieu of having doors at the rear end 12, is provided with side doors 13 which normally close a side opening 14. When these doors are closed, the automobile does not differ essentially in appearance from a standard sedan.

My invention provides a movable platform which may be comprised of perimetric angle members 15, which may be nickel, or silver plated, and which may be secured together in any suitable manner, such as by welding. Floor boards 16 are arranged within the angle members 15, these floor boards being flush with the top of the upper legs of the angles 15, as shown, and being secured in place by suitable angle brackets 17 which may be secured in place, as by rivets 18. For movably supporting the platform, rollers or castors 20 are provided, as clearly shown in Figs. 3 and 4. The castors 20 comprise a roller 21 which is rotatably supported by a supporting frame 22, there being a suitable bracket 23, which is secured to the frame 15 for attaching the frame 22 to the platform.

For guiding the platform through a designated path, I provide guide members 25 and 26, which are situated substantially as shown in Figs. 1 and 3. As shown clearly in Fig. 2, each of the guide members 25 and 26 may comprise a bracket 27, which is secured by rivets 28 to a cross angle 29, each cross angle

29 being secured to the perimetric angles 15 by suitable brackets 30. Extending through each of the brackets 27 is a shoulder pin 32 which has a head 33 for retaining a guide roller 35 in place on the lower end thereof, there being a nut 36 for securing each pin 32 rigidly in a bearing bracket 27. In the floor 37 of the hearse 11 there is provided a pair of grooves 38 and 39. From Fig. 1 it will be seen that the groove 38 is substantially straight, whereas the groove 39 is sinuous, this being for the purpose of properly guiding the platform from normal position, as shown by the full lines in Fig. 1, into a receiving position, as indicated by the dotted lines 40 of this figure. As clearly shown in Fig. 2, each of the grooves 38 and 39 consists of groove bars 41 which may be nickel-plated for appearance, and which are secured in slots 42 by means of suitable bolts 43. Centrally and below the groove bars 41 there is provided a channel 44, into which a guide roller 35 extends. It will be seen that the adjacent edges 46 of the guide bars 41 extend inwardly above the limits of the central groove 44. The roller 35 provides a head 47 which at its upper face 48 engages with the lips 46 of the guide bars 41 and is thereby retained in place in the central groove 44. It will be seen that this interengagement between the faces 48 and the lips 46 prevents an upward movement of the rollers 35 but permits a lateral movement thereof.

As shown in Fig. 5, a means for locking the platform in normal position consists of a locking pin 50 which extends through a hole 51 in a lug 52 of a bracket 53, this bracket 53 being secured to the platform, as by rivets 54. A dog 56 is provided in the lug 52, as shown, this dog being forced into one of the slots 58 of the pin 50 by a spring 59. When the locking pin 50 is in the position shown by the full lines in Fig. 1, the platform is free to move. By pulling outwardly on the dog 56, the locking pin 50 is free to move into the position indicated by the dotted lines 60 of this figure, the pin when in this position being extended into an opening 61 in the floor 37 and thereby renders the platform immovable.

In order to assure the retaining of the casket in proper position upon the platform, I provide dowels 63 which extend upwardly from the platform, and when the casket is in place thereon, enter into cooperating openings therein.

The operation of my device is substantially as follows:

The hearse, being parked parallel to the curb, the side doors 13 thereof are open as in Fig. 1 to permit access to the interior of the vehicle through the opening 14. The locking pin 50 is then released or moved into a position, as shown by the full lines in Fig. 5, as previously described, thus rendering the platform free to move. The platform is then

swung from the position shown in full lines in Fig. 1 into the receiving position, as indicated by the dotted lines 40 of this figure. A feasible way to accomplish this movement is by gripping the farther side of the platform at the extreme forward end thereof and shifting it into the position substantially as indicated by the dotted lines 65 of Fig. 1. It is then possible for the operator to grip both sides of the platform at the forward end thereof and readily pull it forwardly and sidewise into the position indicated by 40 in Fig. 1. When the platform is in this position, it extends substantially one-half to the exterior of the hearse. This facilitates the placing of a casket thereon by eliminating considerable of the sliding of a casket along the floor of the hearse, as was previously necessary in the old types of vehicles. It will be seen that it is impossible for the platform to tilt because of the interengagement between the rollers 35 and the guide bars 41, as previously described. The casket is then placed upon the platform so that the dowels 63 extend into accommodating openings in the casket, this cooperation tending to preserve the proper position of the casket until it is removed from the platform. The platform is then swung into normal position and the locking pin 50 again inserted into the opening 61 in the floor 37 of the vehicle 11.

By providing guiding means and supporting means which are entirely separate, I am able to produce a platform which is extremely easy to move; this is greatly due to the fact that there is no binding proclivity incurred in the guide rollers because there is no weight thereon.

I claim as my invention:

1. In a hearse, the combination of a vehicle body having a side opening; a rectangular platform longitudinally disposed within said body and supported on the floor thereof for horizontal bodily movement, said platform being of a size preventing its horizontal rotation within the body; and means for automatically guiding the platform when moved in a determined path, to cause one end thereof to travel in a longitudinal path entirely within the body and the opposite end to simultaneously travel in a path transverse of the body and to be projected outwardly through said side opening.

2. In combination with a vehicle: a movable platform supported in said vehicle; and means for guiding said platform through a predetermined path which comprises guide rollers secured to said platform, and guide grooves disposed in said vehicle, said rollers extending into said guide grooves and provided with heads which are confined in said grooves by lips provided by said guide grooves in such a manner as to permit lateral movement and to prevent vertical movement.

3. In a hearse, the combination of: a vehicle body of sufficient size to allow a casket to be disposed therein with its major axis parallel to the ground and substantially parallel to the line of motion of said body, said body having a door at one side thereof somewhat wider than said casket but narrower than the length of said casket; and means cooperatively associated with the casket and 10 floor of the vehicle for automatically guiding said casket in a determined path of movement in such a manner that it is simultaneously swung and advanced through said door.
- 15 4. In a hearse, the combination of: a vehicle body of sufficient size to allow a casket to be disposed therein with its major axis parallel to the ground and substantially parallel to the line of motion of said body, said 20 body having a door at one side thereof somewhat wider than said casket but narrower than the length of said casket; a platform of proper size to support said casket; and automatically guiding means for simultaneously 25 swinging and advancing said platform in a determined path of movement so that said casket may be taken end first through said door.
5. In a hearse, the combination of: an enclosed vehicle body of sufficient size to allow a casket to be disposed therein with its major axis substantially parallel to the ground and substantially parallel to the line of motion of said body, said body having a 30 door at one side thereof; and means cooperatively associated with the casket and floor of the vehicle for so mounting and automatically guiding said casket that it can be 35 swung around into a position to be removed from said body through the door opening with the major axis of said casket at an 40 angle to the line of motion of said vehicle.
6. In a hearse, the combination of an enclosed vehicle body of sufficient size to allow 45 a casket to be disposed therein with its major axis substantially parallel to the ground and substantially parallel to the line of motion of said body, a platform for supporting said casket supported by and bodily movable 50 in a horizontal plane in relation to the floor of said vehicle, and means for automatically guiding said platform upon movement thereof whereby one end of the platform will move in one direction and the opposite end in a direction substantially transverse to the travel of said first named end, said guiding means comprising devices secured to the floor and cooperating devices 55 secured to the platform.
- 60 7. The combination with a vehicle body, a platform supported by and bodily movable in a horizontal plane in relation to the floor of said vehicle, said platform being of a size preventing its horizontal rotation within the body, said body having a door at 65
- one side thereof somewhat wider than the platform but narrower than the length of the platform, guide means secured to said platform and cooperating guide means secured to said vehicle, said cooperating guide means serving to automatically guide the platform and constrain it, when moved, to travel in a single path of movement only, to cause the rear end of the platform to travel longitudinally forward and the forward end to project transversely and outward through the said side opening.
8. In a hearse, the combination of: a vehicle body, of sufficient size to allow a casket to be disposed therein, with its major axis 80 parallel to the ground and substantially parallel to the line of motion of said body a platform for supporting the casket, said casket being of a size preventing its horizontal rotation within the body, said body 85 having a door at one side thereof somewhat wider than said casket but narrower than the length of said casket, and means operative upon the movement of said platform to automatically constrain the same to move in a determined course of movement only, and in such a manner that it is simultaneously 90 swung and advanced through said door.
9. In a hearse, the combination of a vehicle body of sufficient size to allow a casket to be disposed therein with its major axis 95 parallel to the body and substantially parallel to the line of motion of said body, a platform for supporting said casket, and mounted on the floor of said vehicle, said platform and casket being of a size preventing its rotation within the body, said body having a door at one side thereof somewhat wider than said casket but narrower than the length of said casket, and cooperating guiding devices 100 associated with said platform and vehicle for automatically guiding said platform and casket upon movement thereof in such a manner that the platform and casket are simultaneously 105 swung and advanced through said door.
10. In a hearse, the combination of a vehicle body, of a sufficient size to allow a casket to be disposed therein with its major axis parallel to the ground and substantially parallel 110 to the line of motion of said body, a platform movably mounted upon the floor of said vehicle, said platform being of a size preventing its rotation within the confines of said body, said body having a door at one side thereof somewhat wider than the platform but narrower than the length of said platform, and means for guiding said platform, automatically, upon a movement thereof, in such a manner that it is simultaneously 115 swung and advanced through said door, said guiding means comprising a plurality of guiding devices of dissimilar curvature.
11. In a hearse, the combination of a vehicle body of a sufficient size to allow a casket 120

- to be disposed therein with its major axis parallel to the ground and substantially parallel to the line of motion of said body, a platform movably mounted upon the floor of said vehicle, said platform being of a size preventing its rotation within the confines of said body, said body having a door at one side thereof somewhat wider than the platform but narrower than the length of said platform, and means for guiding said platform, automatically, upon a movement thereof, in such a manner that it is simultaneously swung and advanced through said door, said guiding means comprising a straight track 15 and a curved track.
12. In a hearse, the combination of a vehicle body, of a sufficient size to allow a casket to be disposed therein with its major axis parallel to the ground and substantially parallel to the line of motion of said body, a platform movably mounted upon the floor of said vehicle, said platform being of a size preventing its rotation within the confines of said body, said body having a door at one side thereof somewhat wider than the platform but narrower than the length of said platform, and means for guiding said platform, automatically, upon a movement thereof, in such a manner that it is simultaneously swung and advanced through said door, said guiding means comprising a substantially straight track associated with said vehicle and a sinuous track associated with said vehicle, and devices carried by the platform cooperating with said tracks to cause the simultaneous swinging of the platform as it is advanced.
13. The combination with a vehicle, a rectangular platform supported by the floor of said vehicle and adapted to support a casket, said platform being normally disposed longitudinally in relation to the vehicle, a door in a side of said vehicle, and guiding means secured to said platform and cooperating with the guiding means secured to the floor of said vehicle, said guiding means automatically causing a simultaneous swinging movement of the platform through a predetermined path of travel as the same is advanced through said door.
14. In combination with a vehicle, a platform supported by and movable in a horizontal plane in relation to the floor of said vehicle, said platform being of a size preventing its rotation within the confines of the vehicle body, guide means cooperating with one end of the platform to compel it to move in one direction, and a second guide means of dissimilar configuration cooperating with the medial portion of the platform to compel the opposite end thereof to travel in a direction substantially transverse to the travel of said first named end, said guide means automatically constraining the platform to move in a definite path of travel,
15. The combination with a vehicle, a platform of substantially rectangular shape supported by and bodily movable in a horizontal plane in relation to the floor of said vehicle, and means for guiding the platform when moved to constrain it to travel in a single course of movement only, said means comprising a straight track and a sinuous track to cause one end of the platform to move in one direction, and the opposite end in a direction substantially transverse to the travel of the first named end.
16. In a device of the class described, a table provided with a system of slots, a casket bearing device provided with pins slideable in said slots, said slots being disposed so as to turn said casket bearing device from a position transversely of the table at one end thereof to a position longitudinally of the table at the other end thereof, upon being moved in one direction, and the reverse upon being moved in the opposite direction, and anti-friction devices between said table and casket bearing device.
17. In a device of the class described, a table and pair of tracks therein disposed in diverse directions, a portable truck on said table, and guides on said truck cooperating with said tracks, the relative divergence of direction of said tracks operating to change said truck from one position at one end of the table to a position at an angle therewith at the other end thereof, one of said tracks having an angular portion permitting a continued lateral movement of one end of the truck after the other end thereof has come to rest.
18. In a device of the class described, the combination with a hearse-shaped vehicle having an opening in its side, and table therein, a pair of guides following divergent courses in said table, a truck movable on said table, and guide members on the truck cooperating with said guides, the divergence of said guides and contour thereof serving to turn said truck from one position opposite said opening to a position at a right angle therewith at a point remote therefrom.
19. In a hearse, the combination of: a body of sufficient size to allow a casket to be disposed therein in such a position that the major axis of the casket is substantially parallel to the ground and to the line of motion of the hearse, said body having a door opening in one side thereof somewhat wider than said casket but narrower than the length thereof through which the casket may be loaded into or unloaded from the hearse; and means upon which said casket may be supported, said means being so constituted as to automatically swing the axis of the casket towards or away from said position as the casket is moved into or out of the hearse through said door.
20. In a hearse, the combination of: a body

- of sufficient size to allow a casket to be disposed therein in such a position that the major axis of the casket is substantially parallel to the ground and to the line of motion of the hearse, said body having a door opening in one side thereof somewhat wider than said casket but narrower than the length thereof through which the casket may be loaded into or unloaded from the hearse; friction reducing means upon which said casket may be supported; and means for automatically swinging said casket to or from said position as said casket is moved into or out of the hearse through said door.
21. In a hearse, the combination of: a body of sufficient size to allow a casket to be disposed therein in such a position that the major axis of the casket is substantially parallel to the ground and to the line of motion of the hearse, said body having a door opening in one side thereof through which the casket may be loaded into, or unloaded from, the hearse; and cooperating elements associated with said casket and said hearse, one of said elements being automatically guided substan-

tially longitudinally along a fixed path in such a manner that said casket may be swung into or out of said hearse through said door.

22. In a side loading vehicle of the character described comprising in combination a body having a platform longitudinally disposed within said body and supported on the floor thereof for horizontal bodily movement in such a position that the major axis thereof is substantially parallel to the ground and to the line of motion of the platform, said body having an opening in one side thereof wider than the platform but narrower than the length thereof, and means for automatically guiding the platform, when moved, in a substantially determined path to cause one end thereof to travel in a substantially longitudinal path within the body and the opposite end to simultaneously travel in a path transverse to the body and to be projected outwardly through said side opening.

In testimony whereof, I have hereunto set my hand at Los Angeles, California, this 21st day of August, 1924.

WILLIAM H. HEISE.
